UNITED STATES PATENT OFFICE.

JAMES H. RAND, JR., OF NORTH TONAWANDA, NEW YORK.

CARD-INDEX SYSTEM.

1,272,525.

Specification of Letters Patent. Patented July 16, 1918.

Application filed September 18, 1915. Serial No. 51,439.

To all whom it may concern:

Be it known that I, JAMES H. RAND, Jr., a citizen of the United States, and resident of North Tonawanda, in the county of 5 Niagara and State of New York, have invented new and useful Improvements in Card-Index Systems, of which the following is a specification.

This invention relates to card index systems of the overlapping card type, and 10 consists primarily in a series of cards having tongues so disposed that when the several cards of the series are assembled and nested, as hereinafter described, the cards 15 will be interlocked by said tongues, and will also be supported and spaced one above another, with their margins exposed, by reason of the nested and interlocked relation of the several cards and tongues. 20 These and associated features will herein-after be more fully described and particularly pointed out in the claims.

In the accompanying drawings which 25 illustrate certain embodiments of the invention,

Figure 1 is a face view, partly broken away, of several cards embodying the invention, mounted in a frame;

Fig. 2 is an elevation of the reverse side 30 of the interlocked cards shown in Fig. 1;

Fig. 3 is a section on line 3—3 of Fig. 2;

Fig. 4 is a perspective view of one of the individual cards of the kind shown in Figs. 1 to 3;

Fig. 5 is a perspective view of a modified 35 form of card;

Fig. 6 is a sectional view of a series of interlocked cards of the kind shown in Fig. 5;

Fig. 7 is a face view, partly broken away, 40 of a series of cards of another form mounted in a frame;

Fig. 8 is a perspective view of one of the individual cards shown in Fig. 7;

Fig. 9 is a sectional view of a series of 45 cards of the form shown in Figs. 7 and 8; and

Fig. 10 is a perspective view of a card containing still another modification.

In card systems of the overlapping card type as heretofore used, the cards are supported by and hinged to bars or strips, which serve both as supports and spacers, said bars or strips being held at their ends 50 in the guide channels of a suitable frame. In the present invention the overlapping

cards are provided with tongues which support the cards one above another and space the cards relatively to each other, and which also interlock the cards in such manner that 55 when the cards are assembled no card can be removed from the series. This construction prevents the abstraction, either through accident or design, of any card from the series, dispenses with the necessity of relatively heavy and costly supporting and spacing bars, and if desired admits of forming the card with its supporting and spacing means out of an integral sheet of paper, cardboard, or the like. When the cards are 60 mounted in a flanged frame they are provided with laterally extending projections to engage the guide flanges of the frame, but as such projections do not perform the functions of spacing and supporting 65 the cards one above another, as do the supporting bars heretofore used, they may be made of comparatively light material, such as the material of the card itself, since they have merely to prevent the cards from falling 70 out of the frame. Each card is also preferably hinged in the manner herein-after explained to facilitate inspection.

Referring first to the form shown in Figs. 1 to 4, A represents a frame of usual construction, having inwardly turned guide flanges a forming channels to receive the laterally extending projections of the cards.

Each card B is made with one or more tongues b (two such tongues being shown 85 in the figures under discussion) the base of which is spaced from one edge of the card, while the tongue extends approximately flatwise of the card toward the opposed edge of the card. These tongues are 90 preferably V-shaped in form and may be cut out of, and integral with the body of the card. When the several cards of a series are assembled the margin of each card B is 95 nested between the tongue or tongues and the body of the next adjacent card in the series. Thus the cards are spaced by said tongues relatively one to another with their 100 margins projecting beyond one another, as best shown in Figs. 1 and 2, and the cards 105 are also relatively interlocked by said tongues. The base of each tongue, spaced from one edge of the card, constitutes the line on which the card is supported by, and spaced relatively to, its neighbor.

Instead of mounting the cards in the frame 110 as shown in Fig. 1, they might be mounted

- in reverse position as shown in Fig. 2, in which case the upper exposed margins instead of the lower margins, would be used for names or other indexed matter; or the 5 cards could be merely inverted top for bottom, with either the obverse or reverse side facing outward, in which case the overlapping cards would be upstanding instead of downhanging.
- 10 To facilitate manipulation and inspection of the cards, each is made with a hinge b' , connecting the portion of the card which carries the tongue or tongues b with the free portion or flap portion. The hinge is preferably made integrally of the card itself by means of a crease, or other weakened portion, and is located in the body of the card within the area limited by the line of support passing through the base of the tongue 20 or tongues, that is, the hinge is at or below said line of support, so that the hinged part of the card may be swung on the relatively fixed part of the card which carries the tongue or tongues without moving or affecting the position of the tongues. In 25 Figs. 1 to 4 the hinge b is located in a line somewhat removed from the base of the tongues and just beyond or substantially coincident with the ends of the tongues, so that no part of a card which is overlapped 30 by a tongue will be swung on the hinge—a construction particularly advantageous when the cards are used in the position shown in Fig. 2.
- 35 In the modification shown in Figs. 5 and 6 the cards B^2 are identical with those of Figs. 1 to 4 save that the hinge b^2 instead of being removed from a line passing through the base of the tongues b , is substantially in that line, and is therefore still located within and not beyond the area limited by that line.
- Referring now to the form shown in Figs. 7, 8 and 9, the card B^3 is folded over at the 45 top, and the fold secured to the body of the card by suitable means such as a line of staples c . The free edge of the fold beyond the staples constitutes a single tongue b^3 the base of which is determined by the fastening means c , spaced from the proximate edge of the card, while the tongue extends substantially flatwise of the card toward the opposite edge. The cards are nested and interlocked as already described, by inserting the 50 margin of one card between the tongue and body of the next card. The tongues b^3 perform the same functions as the tongues b of the other form. Although the tongues b^3 are preferably made integral with the card bodies and folded over, they might be made of separate pieces of paper or other sheet material fastened to the card bodies in the position shown. The hinge in the card is shown at b' a little removed from the base of the tongue b^3 .

The cards thus nested and interlocked, are supported and spaced by the tongues, and could be used in a suitable box or receptacle without other retaining means. When the cards are to be used in a vertical frame A, 70 of the so-called visible index type, they are provided with projections d , extending laterally from the card and engaging the guide flanges a of the frame. These projections d are preferably formed of the same sheet 75 material as the card itself, and integral therewith, and extend laterally from each end of that margin of the card which lies between the base of the tongues and the proximate edge of the card. The projection 80 need not be of stout material like the supporting and spacing bars of overlapping card index systems heretofore used, since they are required merely to prevent the cards from falling out of the frame while 85 the weight of the cards upon one another is supported, and the spacing is effected, by the tongues.

In order to afford additional interlocking means, each projection d may be made wider 90 in its vertical dimension than the distance between the base of the tongue and the proximate edge of the card, so that successive projections overlap one another under the guide flange a , as shown in Figs. 1, and 95 7, when the series of cards is assembled in the frame.

In the modification shown in Fig. 10, the card B^4 , the folded over tongue b^3 and the fasteners c , are substantially the same as 100 the corresponding parts in Figs. 7 to 9. The projections for holding the card in the frame consist of the ends of a rod e , inserted in the loop of the fold between the fasteners c and folded edge of the card. As these projections neither support the weight of the cards, nor constitute the spacing means, the rod may be as light and slender as desired, and need not have any spacing devices at its ends as has heretofore been necessary.

I claim:

1. In a card system, a series of overlapping cards, each having a tongue, the base of said tongue being spaced from one edge of the card and the tongue extending from its base toward the opposite edge of the card, each card being provided with a hinge connecting that portion of the card carrying the tongue and the body of the card and the margin of each card being nested between the tongue and body of the next card in the series, whereby said cards are interlocked by said tongues and are spaced by said tongues relatively to one another with their margins projecting one beyond another.
2. In a card system, a series of overlapping cards, each having a tongue, the base of said tongue being spaced from one edge of the card and the tongue extending from its base toward the opposite edge of the

- card, each card being provided with a hinge connecting the portion carrying the tongue with the flap portion and located within the area limited by a line passing through the base of the tongue, and the free edge of the card, and the margin of each card being nested between the tongue and body of the next card in the series, whereby said cards are interlocked by said tongues and are spaced by said tongues relatively to one another with their margins projecting one beyond another.
3. In a card system, a series of overlapping cards, each having a tongue, the base of said tongue being spaced from one edge of the card and the tongue extending from its base toward the opposite edge of the card, each card being provided with a hinge connecting the portion carrying the tongue with the flap portion and located in a line removed from the base of the tongue and between the base of the tongue and the free edge of the card, and the margin of each card being nested between the tongue and body of the next card in the series, whereby said cards are interlocked by said tongues and are spaced by said tongues relatively to one another with their margins projecting one beyond another.
4. In a card system, a series of overlapping cards, each having a tongue, the base of said tongue being spaced from one edge of the card and the tongue extending from its base toward the opposite edge of the card, each card being provided with a hinge formed by a crease in the body of the card within the area limited by a line passing through the base of the tongue, and the free edge of the card, said cards being interlocked by said tongues and spaced by said tongues relatively to one another with their margins projecting one beyond another.
5. In a card system, a series of overlapping cards, each having a tongue formed integrally of the same sheet material as the card, the base of said tongue being spaced from one edge of the card and the tongue extending from its base toward the opposite edge of the card, each card being provided with a hinge connecting that portion of the card carrying the tongue and the body of the card and the margin of each card being nested between the tongue and body of the next card in the series, whereby said cards are interlocked by said tongues and are spaced by said tongues relatively to one another with their margins projecting one beyond another.
6. In a card system, a series of overlapping cards, each having a tongue cut out of the body of the card, the base of said tongue being spaced from one edge of the card and the tongue extending from its base toward the opposite edge of the card, each card being provided with a hinge connecting that portion of the card carrying the tongue and the body of the card and the margin of each card being nested between the tongue and body of the next card in the series, whereby said cards are interlocked by said tongues and are spaced by said tongues relatively to one another with their margins projecting one beyond another.
7. In a card system, a series of overlapping cards, each having a tongue formed integrally of the same sheet material as the card, the base of said tongue being spaced from one edge of the card and the tongue extending from its base toward the opposite edge of the card, and the margin of each card being nested between the tongue and body of the next card in the series, whereby said cards are interlocked by said tongues and are spaced by said tongues relatively to one another with their margins projecting one beyond another, and a pair of laterally extending projections on each card formed integrally of the same sheet material as the card adapted to engage a frame.
8. In a card system, a series of overlapping cards, each having a tongue formed integrally of the same sheet material as the card, the base of said tongue being spaced from one edge of the card and the tongue extending from its base toward the opposite edge of the card, and the margin of each card being nested between the tongue and body of the next card in the series, whereby said cards are interlocked by said tongues and are spaced by said tongues relatively to one another with their margins projecting one beyond another, and a pair of laterally extending projections on each card adapted to engage a frame.
9. In a card system, a series of overlapping cards, each having a tongue, the base of said tongue being spaced from one edge of the card and the tongue extending from its base toward the opposite edge of the card, and the margin of each card being nested between the tongue and body of the next card in the series, whereby said cards are interlocked by said tongues and are spaced by said tongues relatively to one another with their margins projecting one beyond another, and laterally extending projections on each card adapted to engage a frame, the vertical dimension of said projections being greater than the distance between the base of the tongue and the proximate edge of the card, whereby the projections of successive cards overlap when the series is assembled in a frame.
10. In a card system, a series of overlapping cards, each having a tongue, the base of said tongue being spaced from one edge of the card and the tongue extending from its base toward the opposite edge of the card, and the margin of each card being nested between the tongue and body of the

- 4
- next card in the series, whereby said cards are interlocked by said tongues and are spaced by said tongues relatively to one another with their margins projecting one beyond another, and projections on each card adapted to engage a frame, extending laterally from opposite ends of that margin of the card lying between the base of the tongue and the proximate edge of the card. 50
- 5 11. A card having a tongue the base of which is spaced from one edge of the card, said tongue extending from its base toward the opposite edge of the card, and a pair of projections extending laterally from opposite ends of that margin of the card lying between the base of the tongue and the proximate edge of the card. 55
- 10 12. A card having a tongue formed integrally with the card, said tongue having its base spaced from one edge of the card and extending from its base toward the opposite edge of the card, and a pair of projections formed integrally with the card and extending laterally from the ends of that margin of the card lying between the base of the tongue and the proximate edge of the card. 60
- 15 13. In a card system, a series of overlapping cards each having a tongue, the base of said tongue being spaced from one edge of the card and the tongue extending from its base toward the opposite edge of the card, one margin of each card being confined between the tongue and body of the next card of the series whereby said cards are interlocked with their margins projecting one beyond the other, and projections extending laterally from opposite ends of that portion of the card carrying the tongue and adapted to engage a frame. 65
- 20 14. In a card system, a series of overlapping cards, each having a tongue formed integrally of the same sheet material as the card, the base of said tongue being spaced from one edge of the card and the tongue extending from its base toward the opposite edge of the card, and a pair of projections extending laterally from opposite ends of that portion of the card carrying the tongue and adapted to engage a frame. 70
- 25 15. In a card system, a series of overlapping cards, each having a tongue arranged adjacent to one edge of the card and extending toward the opposite edge of the card, and the margin of each card being nested between the tongue and body of the next card in the series, whereby said cards are interlocked by said tongues and spaced by said tongues relatively to one another with their margins projecting one beyond another, and projections extending laterally from opposite ends of that edge of each card adjacent to the tongue and adapted to engage a frame. 75
- 30 16. In a card system, a series of overlapping cards each having a tongue, the base of said tongue being spaced from one edge of the card and the tongue extending from its base toward the opposite edge of the card, one margin of each card being confined between the tongue and body of the next card of the series whereby said cards are interlocked with their margins projecting one beyond the other, projections extending laterally from opposite ends of that portion of the card carrying the tongue and adapted to engage a frame, and each card being provided with a hinge connecting the body portion of the card to the portion thereof carrying the tongue. 80
- 35 40 45
14. In a card system, a series of overlapping cards, each having a tongue formed integrally of the same sheet material as the card, the base of said tongue being spaced from one edge of the card and the tongue extending from its base toward the opposite edge of the card, and a pair of projections extending laterally from opposite ends of that portion of the card carrying the tongue and adapted to engage a frame. 85

Signed by me at North Tonawanda, New York, this 11th day of September, 1915.
